UNITED STATES PATENT OFFICE.

JOHN K. STEWART, OF NEW YORK, N. Y.; JULIA B. STEWART EXECUTRIX OF SAID
JOHN K. STEWART, DECEASED.

STARTER FOR INTERNAL-COMBUSTION ENGINES.

1,242,997.

Specification of Letters Patent. Patented Oct. 16, 1917.

Application filed November 10, 1915, Serial No. 60,728. Renewed February 26, 1917. Serial No. 151,147.

To all whom it may concern:

Be it known that I, JOHN K. STEWART, a citizen of the United States, residing at New York city, in the county of New York and State of New York, have invented a new and useful Improvement in Starters for Internal-Combustion Engines, of which the following is a specification.

The purpose of this invention is to provide an improved device for starting the internal combustion engine of an automobile, by the reaction of a spring which is wound by the running of the engine. It consists in the elements and features of construction shown and described as indicated in the claims.

In the drawings,—

Figure 1 is a plan view of a portion of the forward end of a motor vehicle and the engine thereon—equipped with a device embodying this invention.

Fig. 2, rear end elevation of the starter casing.

Fig. 3 is a section at the line 3—3 on Fig. 1.

Fig. 4 is a vertical section at the line 4—4 on Fig. 1.

Fig. 5 is section at the line 5—5 on Fig. 1.

Fig. 6 is a section at the line 6—6 on Fig. 5.

Fig. 7 is a section at the line 7—7 on Fig. 5.

Fig. 8 is an enlarged detail section in the same plane as Fig. 5 through the interlapped portions of the two members of the starting shaft, showing their clutch engagement, and the detail construction for retaining grease in the casing.

Fig. 9 is a detail section in the same plane as Fig. 5 showing the coupling of the two members of the starting shaft with said members in different relative positions, from Fig. 5.

Fig. 10 is a horizontal sectional view of the casing, disclosing a top plan view of the power spring and winding-up train therein.

Fig. 11 is a transaxial section at the line 11—11 on Fig. 10.

Fig. 12 is a section at the line 12—12 on Fig. 10.

Fig. 13 is a detail side elevation showing the planet pinion and a segment of the final gear and of the master gear of the planetary gear train for winding up power spring.

Fig. 14 is an enlarged detail edge view of the master gear and the final driven gear of the planetary train at the point in their circumference at which they have their teeth alined, the planet pinion being shown in 60 dotted line.

Fig. 15 is a similar view at a point in the circumference in the gears at which their teeth are not alined, the planet pinion at that position being shown in full line. 65

The starting mechanism which constitutes this invention is shown in the drawings applied to a familiar type of motor vehicle by substitution of the mounting parts of the starter in the position and place of certain 70 familiar parts of such motor vehicle and its engine, which parts will be referred to but not shown in the drawings.

In the drawings, A represents a portion of the chassis or frame structure of the vehicle, 75 A¹, being the forward transverse bar which is situated above the forward spring partly shown at B. C is the fan pulley on the engine crank shaft D.

In place of the bearing pillow for the forward end of the engine frame or crank case, E, and the journal bearing of the customary starting shaft, which pillow together with the customary starting shaft and its crank is discarded for mounting on the 85 vehicle and connecting with its engine the present starting device, there is mounted on the forward transverse frame bar, A¹, the starter casing, 1, having at the rear end a flange, 1^a, fitted to the seat on the bar, A¹, 90 from which the starting shaft bearing pillow has been removed together with its crank. The flange, 1^a, has a capped seat, 1^v, for the rear terminal, e, of the engine frame or crank case, in place of the similar seat with which the removed pillow was provided. In the casing, 1, there is journaled as hereinafter more particularly described the starting shaft comprising the rear member,—hereinafter referred to as the engine-connected 95

member—2, which enters through,—but does not require any bearing support in,—the rear terminal, e, of the engine frame at the bearing aperture, e², vacated by the removed starting shaft. The rear squared end 2^x of 100 this engine-connected starting shaft member, 2, engages for sliding in and revolving with it, a cup-shaped terminal, 3, which is proportioned to enter the annular cavity of the fan pulley, C, in which the clutch-member 105 110

of the customary starting shaft enters for engaging with the clutch pin, 3^b, which customarily also secures the fan pulley to the engine crank-shaft; and said clutch-pin being first withdrawn to admit the cup-shaped terminal, 3, into the annular cavity of the fan pulley and then replaced passing through the pin holes, 3^a, in the terminal, 3, secures the latter, and thereby the starting shaft member, 2, permanently to the fan pulley and thereby to the engine crank-shaft. The engine-connected starting shaft member, 2, has an axial bore in its rear end in which is lodged a coiled spring, 4, which reacts between the bottom of the bore and end of the engine crank shaft which is exposed at the center of the hub of the fan pulley for thrusting the shaft member, 2, forward at its sliding connection with the terminal, 3. For transmitting the thrust of the spring, 4, to the engine shaft a shouldered center-pin, 4^a, which telescopes in the bore of the shaft and whose spindle, 4^b, reduced in diameter to form the shoulder, 4^c, extends within the coiled spring, has its cone point, 4^d, seated in a center conical socket bored in the end of the shaft, and by this means the shaft member, 2, is steadied and kept axially aligned with the engine shaft, preventing rattling which might otherwise occur at this connection which is necessarily somewhat loose to insure freedom of sliding of the shaft member, 2, in the terminal, 3.

35 The casing, 1, comprises two distinguishable chambers or housings, 1^b and 1^c. In the chamber 1^b there are housed the several members of a one-way drawing clutch device, hereinafter more particularly described, which connects the rear or engine connected member of the starting shaft with the hereinafter mentioned forward member hereinafter called the prime moving member thereof. The second chamber 1^c houses the motor spring, 10, and the gear train for winding up that spring. The two members of the casing forming these two housings or chambers are telescoped, the latter upon the former, making a drive fit at 1^d, and 50 are further secured against slippage by screws 1^e.

55 The forward or prime-moving member, 7, of the starting shaft is tubular, and has its axial cavity of suitable diameter to receive within it the ratchet clutch head 2^a with which the rear shaft member 2 is terminated at its forward end, for engagement by an emergency starting crank as hereinafter explained. Said rear shaft member, 2, has 60 made fast to it just back of the ratchet clutch head 2^a a fitting, 11, forming at the forward end of the shaft member 2, an annular chamber 11^a, into which the rear end of the forward shaft member 7 extends. This fitting 65 comprises a ball race 2^b for the ball-bearing

indicated by the balls 2^c, by which the two shaft members 2 and 7 are journaled respectively in and on each other; and it comprises also an annular axially elongated race 2^d for a plurality of clutch balls, 2^e positioned at equal intervals around the intruded end of the shaft member, 7, by means of a like number of seats 7^a distributed at equal intervals in its circumference, said seats being each formed by a spheroidal 70 incut in the outer face of the shaft member 7, such incut having its bottom sloped relatively to the circumferential surface of the shaft from the deepest point of the spheroidal incut out of the surface in the line 75 preferably curved eccentrically of the shaft as seen in Fig. 7 so as to constitute a slope with respect to the circumference of the shaft more gradual than a chord through said deepest point. When the shaft is at 80 rest a certain number of the clutch balls will gravitate along the inclined bottom of their said seats, and be in wedging relation between said seats and the race 2^d, and will clutch the shaft members, 2, and 7, to each 85 other, for driving originating with the prime moving shaft member, 7, in the direction in which that member is actuated by the motor spring, 10, as hereinafter more particularly described, and to permit their 90 relative rotation when the shaft, 7, is reversely driven, or when the rotation in the first mentioned direction originates with the engine connected shaft member, 2.

95 Within the forward end of the fitting 11 100 there is formed one member of the ball race for a ball bearing, 2^b which is provided between said fitting, and thereby between the rear shaft member 2, and the forward shaft member, 7. Another ball-retaining 105 member of said race is a sleeve, 14, mounted for sliding on the shaft member, 7, and connected therewith by pins, 14^a extending inward from said sleeve through slots, 7^c, in the tubular shaft member, 7, and projecting 110 in the cavity of said tubular shaft member and engaging a sleeve, 15^c, which is positioned within said shaft member, 7, and operated as hereinafter described.

115 Housed in the chamber formed by the member 1^c of the casing, there is positioned at the forward end the motor spring, 10, having its inner end made fast to the drum 21 which is keyed fast to the prime-moving shaft member, 7, and at its outer end it is 120 made fast to the case member, 1^e by the bolt or pin, 10^a, inserted through the forward wall of the casing, and engaging by its rear end one of the radial ribs 1^f, which are provided primarily for the purpose of stiffening the casing.

125 25 is a planet-gear-carrying disk having a hub or flange 25^a which is provided with ball bearings 51 in the head or forward end formed by a steel ring 50 of the member, 130

1^b, of the casing, which forms the rear end of the chamber which incloses said spring and gear train as above stated. The prime-moving starting shaft member, 7, obtains a ball bearing 25^a in said disk, 25, as more particularly hereinafter described. Keyed fast into the shaft member, 7, immediately adjacent to the balls 25^a, and forming one side of the ball race for the same, there is a gear 27. Journalized on said shaft member, 7, with interposed ball bearings, 33—33, hereinafter more particularly described, there is a gear 28 of the same diameter as the gear 27 but having one tooth less than said gear 27. On the disk 25 mounted for rotation about their axes which are positioned in the circumference of a circle about the axis of the shaft, 7, there are three gear pinions, 29, 29^a and 29^b, whose width is such that they each engage both the gears 27 and 28. For such engagement the pinion 29 has its teeth continuous across its face so as to engage simultaneously both the gears 27 and 28 whose teeth coincide at that side of their circumference at which they are meshed with the said pinion 29. By reason of the fact that the gear 27 has one tooth less than gear 28 it will occur that when the teeth of the two gears 28 and 27 coincide at a given point in their circumference, as, for an engagement of both gears by the continuous teeth of the pinion 29 intermeshed with both of the gears 27 and 28, the teeth of said two gears at a distance one-third of the circumference—120 degrees—around from the point at which the teeth coincide or are aligned as mentioned, will be offset or misaligned to the extent of one-third the distance apart of consecutive teeth; and in order therefore to adapt the pinions 29^a and 29^b to mesh properly with the teeth of both the gears 27 and 28, said pinions are constructed with two banks of teeth offset or misaligned with respect to each other, to the extent of one-third the inter-tooth-space, one of said two pinions thus constructed having teeth of the bank positioned for meshing with the gear 27 offset from those of the other bank said one-third inter-tooth-space in one direction around the pinion, and the other having its bank of teeth meshing with the gear 28 offset a like distance in the opposite direction, so as to correspond with the misalignment or circumferential offsetting of the teeth of the gears 27 and 28 at the points situated respectively 120 degrees in opposite directions circumferentially from the pinion 29, that is, at the points at which said pinions 29^a and 29^b respectively are situated. By this means all three of the pinions 29, 29^a and 29^b are equally effective in respect to their engagement with both the gears 27 and 28 for transmitting rotary motion in the operation of the planetary gear system of which they are parts; and the stress upon the engaged teeth in such transmission is thereby rendered only one-third what it would be if only a single pinion 29 were employed in the transmission. In view of the very severe stress to which the teeth 70 of this planetary gear train are subjected in the work to be done in the winding of the spring, and the importance of compactness in the structure, this expedient, permitting the employment of relatively fine teeth, and therefore relatively small gears, is considered of importance in this structure.

Rigid, and if desired formed unitarily, with the gear 28 there is provided a locking disk 28^a which is most conveniently provided with the same number of teeth for locking as the gear 28 has for meshing with the planetary pinions 29, 29^a and 29^b said teeth of the locking disk being for engagement with the teeth of a locking device 80 which consists of a dog 30 pivoted on an eccentric wrist 31^a of a rock shaft 31 journalized in an appended member 1^c of the casing and provided with means hereinafter described for rocking it to cause the eccentric wrist to withdraw the dog from or thrust it toward the gear 28^a for disengagement and engagement of the teeth of the segment terminal 30^a of said dog 30, said segment terminal comprising a sufficient 90 number of teeth to afford engagement with a like number of teeth of gear 28^a to safely hold said gear without undue stress upon any one of the teeth thus engaged. A spring 30^b reacts in the dog to rock it about the 100 wrist in the reverse of its locking direction. The toothed segment terminal 30^a of the dog is eccentric to the axis of the eccentric wrist which is the fulcrum or pivot of the dog, and at all positions of that wrist possible in the operation of the device said segment terminal is eccentric also to the rock shaft 31; and the rock shaft axis and the wrist axis are so located relatively to segment terminal and to the axis of the locking gear 28^a that when said three axes are substantially in the same plane,—that is when the rock shaft has been turned to bring the eccentric wrist axis into the plane of the other two axes,—the segment terminal 30^a is meshed to the fullest extent with the locking gear 28^a, which might be expressed to the effect that at that condition the plane containing the axis of curvature of the segment terminal and the axis of the locking gear 28^a substantially bisects the segment. This arrangement gives the greatest locking or holding efficiency with a given tooth-depth in the locking gear 28^a 110 and the segment terminal, because the locking occurs with the maximum number of teeth engaged. The several axes mentioned are also so located relatively that when the rock shaft axis, the wrist axis and the axis of the locking gear 28^a are in the same plane 120

130

as described, with the wrist axis between the other two for holding the locking gear at locking position, the axis of curvature of the segment terminal 30^a is situated at the side of said plane from which the engaged circumference of the locking gear would be moved toward said plane in the rotation of the planetary gear-carrying disk if said locking gear were not locked. This makes the dog self-stopping at the locking position described, because the rotation of the locking gear 28^a in the direction in which alone it could be rotated by the reaction of the spring 10, would have to cause the dog, whether turning about its own pivot on the wrist or turning together with the wrist about the axis of the rock shaft, to crowd apart the axis of the gear 28^a on the one hand and the axes of the rock shaft and wrist on the other hand, which is impossible, because the three axes being in line the pressure cannot operate to fold the joint at the wrist, and the rock shaft bearing is absolutely fixed with respect to bearing of the shaft of the gear. But when the operator by the means provided rocks the rock shaft in the direction for carrying the wrist out of line with the other two axes, and back toward the side from which the locking gear 28^a would be revolved by the motor spring 10, far enough to make the distance of the wrist axis from the locking gear sufficient to accommodate the dog at the most remote tooth of its segment terminal between the wrist and the locking gear, the motor spring 10 will rotate the locking gear which in turn engaging the segment terminal of the dog will swing the latter about the wrist, feeding the segment out of mesh with the locking gear, and the rock shaft being rocked a little farther in the same direction, the spring 30^b acting on the dog tending—but only with slight stress—to swing it back about the wrist, will swing it back clearing the locking gear to a position, shown in dotted line in Fig. 6 at which it is ready to be moved into engagement of its segment terminal with the locking gear, as at the commencement of the cycle of movements described. For operating the rock shaft 31 there is connected to it a flexible or jointed shaft member 44 whose universal joints or flexibility adapt it to communicate the necessary rocking movement to the shaft from a handle not shown, which may be journaled at a convenient point on the dash within reach of the operator.

Double ball bearings 33—33 interposed between the shaft member 7 and the gear 28 have their respective races laterally formed at one side by the side of the gear 27 and at the opposite side by a hardened steel ring 34 interposed between the end of the drum to which the spring is attached 65 and the proximate side of the gear, 28, the

balls of the two sets being spaced apart by any suitable number of spacing washers, 35, which form the proximate sides of the two ball races. At the opposite end of the drum there is a hardened steel washer 36 forming one side of a ball race for ball bearings 37 interposed between the shaft member, 7, and the casing, the outer member of the ball race being a hardened steel ring 38 the lateral wall opposite the steel ring 38 being the inner surface of the casing.

The sleeve 15 has a threaded engagement at 15^a with the hollow shaft member, 7, within which said sleeve is situated projecting beyond the forward end of said shaft member, 7. At the protruding portion said sleeve has secured to it the inner end of helical spring 40 whose outer end is secured to the casing 1^c, said spring being coiled in the proper direction to be wound up or tightened by the rotation of the sleeve, to which the inner end is attached, in the direction in which the shaft member, 7, is rotated in the running of the engine; that is to say, in the direction for winding up the spring 10.

The rear edge of the hub of the disk 25^a which carries the planetary gear pinions is formed as an annular ratchet-toothed clutch member 25^e projecting rearwardly and adapted to engage with a correspondingly annular ratchet-toothed clutch member 11^b which is formed at the forward end of the fitting 11.

The engaging shoulders of the clutch 100 teeth of these co-operating clutch members are very slightly undercut so as to resist longitudinal movement of the parts for disengagement of the clutch shoulders when they are in working engagement and under the stress of rotation transmitted between them. This undercut is calculated to be sufficient in view of the rotative force transmitted through the clutch connection, to resist the rearward thrust which might be transmitted by the sleeve 15 operating against the pins 14^a for pushing the collar 14 rearward against the ball bearings 2^e which operation, whenever it might occur, would force the rear of said two clutch members 115 25^e and 11^b rearward against the resistance of the spring, 4, for disengaging said clutch members. It will be evident that such rearward thrust of the sleeve 15 would result upon rotation at the threaded engagement 120 of said sleeve 15 with the hollow shaft member 7, in one direction while the sleeve 15 was prevented from rotation; and it will be seen that so long as such thrust is prevented the sleeve 15 will rotate with the prime moving shaft member 7, and no action will occur between the two at their threaded engagement. This condition will continue until by the rotation of the sleeve 15, the spring 125 40 is wound tight; and then further rotation 130

of the sleeve being positively prevented, the continued rotation of the shaft member 7, will force rearward the sleeve 15, (the helical spring being somewhat dished in the 5 operation or originally) and will thereby positively force the clutch member 11^b out of engagement with the clutch member 25^e on the disk 25 thereby terminating the transmission for winding the spring 10. The 10 resistance to the longitudinal movement of the sleeve 15 which was caused by the engagement of the under-cut clutch teeth as described, being no longer operative, the spring 40 will react and uncoiling will screw the 15 sleeve still farther into the shaft member 7 and thus still farther separate the clutch members 25^e and 11^b but only to the extent of the relative longitudinal movement of the shaft members 7 and 2 for which provision 20 is made by the clearance shown at 1^z (Fig. 5) in the casing; and the spring 40 will therefore remain coiled nearly to the full extent until, upon the operator releasing the master gear to permit the power spring to react and 25 uncoil for starting the engine, the shaft member 7 is rotated in the reverse direction by the uncoiling of the power spring 10, which will first cause the spring 40 to be uncoiled and then will screw the sleeve 15 out 30 again to its original position permitting the clutch members 25^e and 11^b to be reengaged ready for rewinding the power spring as soon as the operator reverses the rock shaft 35 for throwing the locking dog into operation to hold the master gear 28.

It will be noticed that the casing 1 affords a bearing for the planetary gear-carrying disk 25, and that that disk affords a bearing for the prime-moving shaft member 7, and 40 thereby said shaft member is supported on the casing, and affords support in turn for the engine-connected shaft member, 2, which is journaled upon it as described by means of the fitting 3, all of which is effected by 45 the following means:—At the opening of the chamber 1^b into the chamber 1^c of the casing there is set fast in the casing a hardened steel ring, 50, which forms the outer member of the race of a ball bearing which 50 is indicated by the balls 51. The inner member or ball seat of this race is formed at 25^e on the outer circumferential surface of the hub or flange 25^a whose rear edge forms the ratchet-clutch member 25^e. On 55 the forward side the disk 25 has formed at its inner circumference the outer seat 25^h of a race for the balls, 25^a, of the ball bearing which is formed between the disk, 25, and the prime-moving shaft member, 7, the 60 gear, 27, having at its rear side about its inner circumference an annular seat 27^e which constitutes the forward side of the race for the balls 25^a.

For convenience of assembling the parts, 65 forward end of the casing, 1, in which is

formed a chamber which accommodates and houses the spring, 40, is closed by a separable cap 1^x; and this cap is secured onto the main body of the case.

The casing, 1, designed to be filled with 70 grease for lubricating the moving parts therein; and to close the casing cavity securely against leakage at the forward end, a felt gasket, 60, is clamped to the case by the casing cap, 1^x, said gasket extending to 75 the sleeve, 15, and hugging the same closely. The supplemental sleeve member 15^e is exteriorly provided with annular grooves 15^d—15^d in which there are lodged annular 80 felt packing rings 15^e which serve to prevent the passage of oil which may escape through the slots 7^e through which the pins 14^a extend; one of said annular grooves being at one side and the other at the other side of the pins. For similar purposes there may be 85 provided a packing ring 60^b lodged within the rear end of the shaft member 7, just back of the end of the sleeve 15^e and encompassing an interior flange 11^d which is 90 formed on the fitting 11 at the junction with the shaft member, 2, and completely closing the grease cavity at that end.

The operation of this device will now be 95 described through its several stages and in its several functions.

Assuming the device to be mounted on the vehicle and connected with the engine crank shaft as described with the engine at rest, the frictionally operating clutch balls 2^e or some of them being in wedging position 100 will engage the starting shaft members 2 and 7, with each other for rotation originating with the prime-moving shaft member, 7, in the direction for driving the engine from the starting shaft. If the spring 10 105 has been previously wound, the dog 30 being released, the spring, 10, will react for rotating the shaft member 7 and thereby the engine-connected shaft member 2, and the engine crank shaft, thus starting the 110 engine. If the spring has not been previously wound, an emergency crank shaft, which may be the usual starting crank not illustrated with its shaft member having the usual ratchet head,—and which will 115 have been removed from its mounting for substituting the starting mechanism described—will be inserted through the hollow shaft, 7, within the sleeve 15, and engaged with the ratchet-clutch head 2^a of the shaft 120 member 2; and the engine shaft will be rotated thereby for starting the engine. Thereupon the engine running under its own power will wind up the spring 10, rotation being transmitted to the prime-moving 125 shaft member, 7, through the engagement of the clutch members 25^e and 11^b and the planetary gear train. The difference of one tooth between the gears 27 and 28 will cause the gear 27 to be rotated in the reverse direc- 130

tion from the disk 25 and only once for as many rotations of the disk 25 as there are teeth in the gear 27, thus making the winding of a very powerful spring impose a comparatively small stress upon the pinions 29, 29^a and 29^b and the gears to which they are intermeshed.

As constructed and illustrated it is calculated that 250 revolutions of the engine 10 crank shaft will be required to fully wind the spring, so that such winding constitutes a negligible addition to the work imposed upon the engine. While the spring 40 is being wound the spring 40 is also being wound. When the spring-winding rotation of the shaft member, 7, has fully wound up the spring, 40,—while the grip of the clutch teeth of the clutch members, 25^e and 11^b, prevents longitudinal movement of the sleeve, 15, and so prevents rotation of the sleeve, 15, with respect to the shaft member, 7, and so causes the sleeve, 15, to rotate with the shaft member, 7,—the sleeve, 15, being positively held against rotation will be screwed into the shaft member, 7, and at its inner end to push the supplemental sleeve member, 15^e inward; *i. e.*, rearward and cause the latter to slide the collar 14 rearward pushing against the balls 2^c, and forcing the fitting, 11, and the engine-connected shaft member 2 of which it is the rigid forward terminal, rearward until the clutch member 11^b is disengaged from the clutch member 25^e and the prime-moving shaft member 7 is thereby cut off from the winding drive of the engine-connected shaft member 2, and the winding action ceases. In this condition, the dog 30 holding the gear 28 against rotation, the pinion 29, 29^a and 29^b engaged 40 at one end portion with the gear 28 and at the other end portion with the gear 27 holds said gear 27, and thereby the prime-moving shaft member 7 at rest, while the engine continues to run under its own power, the engine-connected shaft member 2 rotating relatively to the shaft member 7 and upon the latter operates noiselessly because so far as the clutch-engagement between said shaft members is concerned, because of the purely frictional or wedge engagement of said clutch device, and the complete disengagement of the clutch members 25^e and 11^b.

When the engine having been stopped is to be started, the operator by rotating the handle of the flexible or jointed shaft—rocking the rock shaft 31 to carry the axis of the crank wrist 31^a away from the locking gear 28^a will lift the heel of the segment head of the locking dog away from the locking gear, 28, and the latter under the stress of the spring operating through the planetary train as a whole and causing it as a whole to rotate about the axis of the starting shaft will rotate in the direction of the engine's forward

rotation feeding the segment head of the locking dog back—*i. e.* rocking the dog about the wrist—until it is out of operative engagement with the locking gear, 28, without the exercise of an appreciable effort by the operator for breaking the frictional grip of the locking gear of the dog, which will be very strong and would cause powerful operating connection to be necessary for disengagement of the dog from the gear if the disengagement had to be effected by directly lifting the dog out of mesh with the locking gear. The rocking movement initially given the rock shaft, 31, by the operator will be completed by the action of the gear, 28^a, on the dog after the said initial rocking has carried the wrist axis a little out of the line connecting the rock shaft axis and the gear axis, but the operator continuing in control of the rocking will continue at a little farther than it will be automatically continued by said gear engagement, and will lift the dog completely out of engagement of the foremost or most eccentrically portioned tooth with the locking gear, and thereupon the spring 30^b will react to swing the dog about the axis of the wrist 31^a back in the opposite direction from that in which the gear engagement has been swinging it, to a position at which its rearmost tooth,—*i. e.*, the tooth nearest the wrist axis—will be substantially in the line from the rock shaft axis to the rear axis, so that upon the operator reversely rocking the shaft 31 after the engine has begun to run under its own power, that tooth of the segment head of the dog will be engaged with locking gear, and the rotation of the latter will feed the dog into full engagement and cause the dog to stop the gear and hold it locked.

I claim:

1. An engine starter comprising two axially aligned rotating members interlapped and having bearings upon each other and provided with one-way driving clutch connections; a casing; a planetary gear train having the member which communicates the planet-wise movement journaled in the casing, and affording journal bearing for the outer of said interlapped rotating members; the central gear member of said planetary train being rigid with said outer of said members.

2. In an engine starter in combination with a casing, an engine-connected shaft member; an axially hollow member outside of and coaxial with said engine-connected shaft member; one-way driving clutch connections between said coaxial members; a planetary gear train having its central gear member rigid with said outside of said coaxial members, a main power spring secured at one end to the casing and at the other

end to a member of the planetary gear train; and a second one-way driving clutch connection between the engine-connected shaft member and a member of the planetary gear train.

3. In an engine starter in combination, a casing, a main shaft, a planetary gear train and a power spring, the power spring being secured at one end to the casing and at the other end to a member of the planetary gear train, and the main shaft having two clutch connections, one with the initial and the other with the final gear member of the planetary train.

15 4. In an engine starter in combination, a casing, a main shaft, a power spring, and a planetary gear train; the power spring being connected at one end to the casing and at the other end to a member of the planetary gear train, the planetary gear train comprising a master gear and means for releasably securing the master gear to the casing against rotation with the train, the power shaft having two clutch connections,

25 one with the initial gear and the other with the final driven gear, exclusive of the master gear, of the planetary gear train.

5. An engine starter comprising the following three elements successively interior each to the preceding, and journaled each upon the next exterior, viz: a casing; an exterior member of a planetary gear train, and an axially hollow member which carries the interior member of such train; and comprising also the master gear of the planetary gear train, and an engine-connected starting shaft member journaled on said axially hollow member.

40 6. An engine starter comprising the following three elements successively interior each of the preceding, and journaled each upon the next exterior, viz: a casing, an outer member of a planetary gear train, and an axially hollow member which carries the inner member of said train, comprising also an engine-connected shaft member clutched to and having a bearing on said axially hollow member.

45 7. In an engine starter, a casing, a starting shaft supported in said casing comprising an axially hollow prime moving member, and an engine-connected member having one-way driving clutch connections with each other; a main power spring operatively connected with the prime moving member; a gear train for winding up the spring having its initial or propelling member journaled in the casing; the hollow prime moving member being journaled in said propelling member, the engine-connected shaft member being journaled within the hollow prime moving member.

8. In an engine starter, in combination a casing, a starting shaft supported in said

casing comprising an axially hollow prime moving member and an engine-connected member having one-way driving clutch connections with each other; a main power spring operatively connected with the hollow prime moving member; a gear train whose final gear is also operatively connected with said prime moving member and whose initial or propelling member has disengageable clutch connections with the engine-connected shaft, said shaft being longitudinally movable in the hollow prime moving member, and means by which the rotation of said prime moving member in opposite directions for winding and in the unwinding of the spring slides the engine-connected shaft member for engagement and disengagement of the last mentioned clutch connection.

9. In an engine starter, in combination with a casing, adapted to be rigidly mounted on the frame, a starting shaft supported in said casing comprising a hollow prime moving member and an engine-connected shaft member having one-way driving clutch connections with each other; a main power spring operatively connected with said prime moving member; a spring-winding gear train whose final gear is also operatively connected with the prime moving member and whose initial or propelling member has disengageable clutch connections with the engine-connected shaft, said engine-connected shaft being loosely engaged for rotation at one end with the engine shaft, and a spring operating to thrust said engine-connected shaft in the direction for engagement of the last mentioned clutch connection.

10. In an engine starter, in combination with a casing adapted to be rigidly mounted on the frame, a starting shaft supported in said casing comprising a hollow prime moving member and an engine-connected shaft member having one-way driving clutch connections with each other; a main power spring operatively connected with the prime moving member; a spring-winding gear train whose final gear is also operatively connected with the prime moving member and whose initial or propelling member has disengageable clutch connections with the engine-connected shaft, said engine-connected shaft being loosely engaged for rotation at one end with the engine shaft; a spring operating to thrust said engine-connected shaft in the direction for engagement of the last mentioned clutch connection, and means operated by the rotation in opposite directions of said hollow prime moving member for engaging and disengaging said clutch connection.

11. In an engine starter, a power spring; a starting shaft comprising a prime moving member and an engine-connected member

having a one-way driving clutch connection; the first member being operatively connected with the power spring for winding it and for being rotated by it in its unwinding; the second member being provided with means for operatively connecting with the engine shaft for rotating and being rotated by the latter; a planetary gear train comprising a motor-spring-connected gear, a 10 master gear, a planetary pinion engaging both gears and a rotary member clutched to and actuated by the engine-connected shaft and actuating the planet pinion; said rotary member and the master gear being both rotatable about the starting shaft; disengageable clutch connections between said rotary member and the engine-connected shaft member; a casing in which the starting shaft members are journaled, and to which 20 the outer end of the power spring is secured; means for locking the master gear non-rotatably in the casing, and means for releasing the locking means to permit the bodily rotation of the planetary train about the 25 axis of the train for rotating the starting shaft.

12. In an engine starter a power spring, a starting shaft comprising a prime moving member operatively connected with the 30 power spring, and an engine-connected member having one-way driving clutch connections; a casing in which the starting shaft members are journaled and to which the outer end of the power spring is secured; 35 the prime moving shaft member being operatively connected with the power spring for winding it and being rotated by it in its unwinding; the engine-connected member being provided with means for operatively connecting it with the engine shaft for rotating and being rotated by the latter; a planetary gear train comprising a power-spring-connected gear, a master gear, a planetary pinion engaging both said gears 45 and a rotary member disengageably clutched to and actuated by the engine-connected shaft and actuating the planet pinion, said rotary member being provided with bearings on the casing, and affording bearings 50 for one member of the starting shaft, said rotary member and the master gear being both rotatable about the starting shaft; the two members of the starting shaft being journaled one upon the other; disengageable 55 clutch members between the engine-connected shaft member and said rotary member of the planetary train; means for locking the master gear non-rotatably to the casing, and means for releasing the locking 60 means.

13. In an engine starter, a power spring; a starting shaft comprising a prime moving member operatively connected with the power spring and an engine-connected mem-

ber having one-way driving clutch connections; a casing in which the starting shaft members are journaled and to which one end of the power spring is secured; the engine-connected shaft member being provided with means for operatively connecting it with the engine shaft for rotating and being rotated by the latter; a planetary gear train comprising a gear fast on the power-spring-connected shaft member, a master gear, a planet pinion engaging both said gears, and a rotary member having disengageable clutch connections with the engine-connected shaft member; disengageable locking means for holding the master gear non-rotatably in the casing; means for disengaging the clutch 80 connections between the prime moving shaft member and said rotary member of the planetary train by the rotation of the engine-connected shaft member in spring-winding directions after a predetermined amount of winding; and means for releasing the master gear holding locking means.

14. An engine starter comprising a starting shaft consisting of two axially aligned members one of which is tubular inter-lapped 90 for a portion of their length and having journal bearings upon each other at transaxial planes, one of said bearings constituting also a one-way driving clutch connection between the two shaft members; a casing; a planetary gear train in the casing having its planet-gear-carrying member journaled in the casing and affording a journal bearing for the starting shaft, whereby the latter is supported in the casing, the bearing of the planet-gear-carrying member in the casing being at a transaxial plane intermediate the plane of bearing of the starting shaft on said member and the plane of the proximate bearing of the shaft members 95 upon each other; a power spring in the casing secured to one of the shaft members the central gears of the planet train being positioned along the shaft between the spring 100 and the planet-gear-carrying member.

15. An engine starter comprising a starting shaft comprising two axially aligned shaft members, one of which is tubular, inter-lapped and provided with ball bearings one upon the other and also having one-way driving clutch connections at their interlapped portion; a casing; a planetary gear train having its planet-gear-carrying member provided with a ball bearing for journaling it on the casing and a ball bearing by which it affords means for journaling the starting shaft upon it, whereby the starting shaft has ball bearing supports on the casing; a power spring having one end connected to one end of the power shaft and the other end to the casing, the central gears of the planetary train being positioned along the starting shaft between the power spring 115 120 125

and the planet-gear-carrying member and having ball bearings on the starting shaft, the casing having additional ball bearing for the starting shaft at the opposite side of the power spring.

16. In an engine starter, a power shaft; a starting shaft comprising a prime moving member operatively connected with the power spring and an engine-connected member having a one-way driving clutch connection; the first member being operatively connected with the power spring for winding it and being rotated by it in its unwinding; the second member being provided with means for operatively connecting it with the engine shaft for rotating and being rotated by the latter; a planetary gear train having its final gear fast on its prime moving shaft member and its planet-pinion-carrying member and its master gear rotatable about the starting shaft; disengageable clutch connection between the engine-connected shaft member and the planet-pinion-carrying member of gear train; a casing in which the starting shaft members are journaled and to which the outer end of the power spring is secured; means for locking the master gear nonrotatably to the casing and means for releasing the locking means to permit the bodily rotation of the planetary train about the axis of the train for rotating the starting shaft.

17. In an engine starter, a power spring; a starting shaft comprising a prime moving member operatively connected with the power spring and an engine-connected member having one-way driving clutch connections; a casing in which the starting shaft members are journaled and to which the outer end of the power spring is secured; the prime moving shaft member being operatively connected with the power spring for winding it and being rotated by it in its unwinding; the engine-connected member being provided with means for operatively connecting it with the engine shaft for rotating and being rotated by the latter, the planetary gear train having its final gear fast on the prime moving shaft member and its planet-pinion-carrying member provided with ball bearings on the casing and affording ball bearings for one member of the starting shaft; and the master gear rotatable about the starting shaft; the two members of the starting shaft being journaled one upon the other by intervening ball bearings; disengageable clutch members between the engine-connected shaft member and the planet-pinion-carrying member of the planetary train; means for locking the master gear non-rotatably to the casing and means for releasing the locking means.

18. In an engine starter, a power spring;

a starting shaft comprising a prime moving member operatively connected with the power spring, and an engine-connected member having one-way driving clutch connections; a casing in which the starting shaft members are journaled and to which one end of the power spring is secured; an engine-connected shaft member being provided with means for operatively connecting it with the engine shaft for rotating and being rotated by the latter; a planetary gear train having its final gear fast on the prime moving shaft member and its planet-pinion-carrying member and the master gear rotatable about the starting shaft; disengageable clutch connections between the engine-connected shaft member and the planet-pinion-carrying member; disengageable locking means for holding the master gear non-rotatably in the casing; means for disengaging the clutch connections between the prime moving shaft and the planet-pinion-carrying member by the rotation of the engine-connected shaft member in spring-winding direction after a predetermined amount of winding; and means for releasing the master-gear-holding locking means.

19. An engine starter comprising a casing; a prime-moving starting shaft member supported in the casing; an engine-connected shaft member; a power spring operatively connected with the prime-moving shaft member for rotating said shaft member; a planetary gear train having its final gear operatively connected for winding the power spring; means by which the engine-connected shaft member rotates the planet-pinion-carrying member of the planetary gear train; a locking dog adapted to engage the master gear of said train; a fulcrum for said dog movably mounted in the casing and means for moving it toward and from the axis of the train, and for holding it at the nearer position.

20. An engine starter comprising a casing; a prime-moving starting shaft member supported in the casing; an engine-connected shaft member; a power spring operatively connected with the prime moving shaft member for rotating said shaft member; a planetary gear train having its final gear operatively connected for winding the power spring; means by which the engine-connected shaft member rotates the planet-pinion-carrying member of the planetary gear train; a locking dog adapted to engage the master gear of said train; a rock shaft journaled in the casing having an eccentric wrist; the locking dog being fulcrumed on said wrist, and means for rocking the rock shaft to carry the wrist toward and from the axis of the master gear.

21. An engine starter comprising a casing; a prime-moving starting shaft member

supported in the casing; an engine-connected shaft member; a power spring operatively connected with the prime moving shaft member for rotating said shaft member; a planetary gear train having its final gear operatively connected for winding the power spring; means by which the engine-connected shaft member rotates the planet-pinion-carrying member of the planetary gear train; a locking dog adapted to engage the master gear of said train; a fulcrum for said dog movably mounted in the casing and means for moving it toward and from the axis of the train, and for holding it at the nearer position; the master gear having a bank of locking teeth, and the dog having its gear locking head formed as a gear segment adapted to mesh with said locking teeth of the master gear and being eccentric to the wrist axis of the dog trending away from said axis in the direction thereabout in which the engagement of the segment with gear progresses as the gear tends to revolve under the stress of the motor spring.

22. An engine starter comprising a casing; a prime-moving starting shaft member supported in the casing; an engine-connected shaft member; a power spring operatively connected with the prime-moving shaft member for rotating said shaft member; a planetary gear train having its final gear operatively connected for winding the power spring; means by which the engine-connected shaft member rotates the planet-pinion-carrying member of the planetary gear train; a locking dog adapted to engage the master gear of said train; a fulcrum for said dog movably mounted in the casing; means for moving it toward and from the axis of the train, and for holding it at the nearer position; and a spring acting on the dog for swinging it about its fulcrum in the direction opposite to that in which the gear tends to force it; and a stop limiting the movement of the dog with respect to its fulcrum support.

23. An engine starter comprising a casing; a prime-moving starting shaft member supported in the casing; a power spring operatively connected with the prime-moving starting shaft member for being wound thereby and for rotating the power shaft in unwinding; means for connecting the prime-moving starting shaft member with an engine shaft; a planetary gear train operatively connecting said means with the prime-moving starting shaft member for winding the power spring, said planetary gear train comprising a master gear and a final driving gear coaxial and of the same diameter and having a differential of one tooth; a planet-pinion-carrier and a plurality of planet pinions distributed circum-

ferentially thereon each meshing both with 65 the master gear and with the final gear; one of said pinions having its teeth continuous for meshing with both said gears at once, the other of said pinions having their teeth formed in two banks offset circumferentially from each other part of an inter-tooth space proportionately to the angular distances of said pinions from the first pinion.

24. An engine starter having in combination with a power spring, engine-connected shaft member and prime-moving shaft member connected with the spring for winding it up; a winding-up train and a clutch connection for driving said train from the engine-connected shaft member; a means for disengaging said clutch connection at a predetermined stage in the spring winding operation comprising a member mounted for travel longitudinally of the spring-winding shaft and having screw-threaded engagement with said shaft for producing such travel by the spring-winding rotation of said shaft, said member having connections for forcing disengagement of the clutch by such travel; an auxiliary spring which is connected to said member for being wound up by rotation of said member with the main-spring winding shaft; means for causing overcomable resistance to disengagement of the clutch member for delaying longitudinal travel and thereby causing rotating said member with the spring-winding shaft until the auxiliary spring is wound tight.

25. An engine starter having in combination with a power spring, engine-connected shaft member, and prime-moving shaft member connected with the spring for winding it up; a winding-up train, and a clutch connection for driving said train from the engine-connected shaft member; a means for disengaging said clutch connection at a predetermined stage in the spring winding operation comprising a member mounted for travel longitudinally of the spring-winding shaft and having screw-threaded engagement with said shaft for producing such travel by the spring-winding-up rotation of said shaft, said member having connections for forcing disengagement of the clutch by such travel; an auxiliary spring which is connected to said member for being wound up by rotation of said member with the main-spring winding shaft, the clutch teeth being undercut for causing overcomable resistance to disengagement of the clutch member for delaying longitudinal travel and thereby causing rotation of said member with the spring-winding shaft until the auxiliary spring is wound tight.

26. An engine starter comprising the following three elements successively interior

- each to the preceding, and journaled each upon the next exterior, viz: a casing; the planet-pinion-carrying member of a planetary gear train, and the prime-moving member of a starting shaft, and comprising also the master gear of the planetary train and the engine-connected member of the starting shaft, both journaled on the prime-moving member of the starting shaft.
27. An engine starter comprising the following three elements successively interior each to the preceding, and journaled each upon the next exterior, viz: a casing; the planet-pinion-carrying member of a planetary gear train, and the prime-moving member of a starting shaft, and comprising also the master gear of the planetary train and the engine-connected member of the starting shaft, both journaled on the prime-moving member of the starting shaft, the prime-moving member and the engine-connected member of the starting shaft being longitudinally movable relatively to each other and having one-way driving clutch connections for driving the engine-connected member, by the prime-moving member, in the direction of proper rotation of the engine shaft.
28. An engine starter comprising the following three elements successively interior each to the preceding, and journaled each upon the next exterior, viz: a casing; the planet-pinion-carrying member of a planetary gear train, and the prime moving member of a starting shaft, and comprising also the master gear of the planetary train and the engine-connected member of the starting shaft both journaled on the prime-moving member of the starting shaft, and a power spring coiled about the prime-moving shaft member and having its inner end operatively connected therewith and its outer end attached to the casing.
29. An engine starter comprising the following three elements successively interior each to the preceding, and journaled each upon the next exterior, viz: a casing, the planet-pinion-carrying member of a planetary gear train, and the prime-moving member of a starting shaft, and comprising also the master gear of the planetary train and the engine-connected member of the starting shaft both journaled on the prime-moving member of the starting shaft, the prime-moving shaft member having an additional bearing on the casing at a transaxial plane remote from the transaxial plane of the bearing of the planet-pinion-carrying member in the casing, and a power spring coiled about and operatively connected with said prime-moving shaft member intermediate said transaxial planes.
30. An engine starter comprising the following three elements successively interior each to the preceding, and journaled each upon the next exterior, viz: a casing, the planet-pinion-carrying member of a planetary gear train, and the prime-moving member of a starting shaft, and comprising also the master gear of the planetary train and the engine-connected member of the starting shaft both journaled on the prime-moving member of the starting shaft, and an engine-connected member of the starting shaft journaled on the prime-moving member of said shaft for rotative and longitudinal movement relative thereto.
31. An engine starter comprising the following three elements successively interior each to the preceding, and journaled each upon the next exterior, viz: a casing; the planet-pinion-carrying member of a planetary gear train, and the prime-moving member of a starting shaft, and comprising also the master gear of the planetary train and the engine-connected member of the starting shaft both journaled on the prime-moving member of the starting shaft, the engine-connected member of the starting shaft being journaled on the prime-moving member of said shaft for rotative and longitudinal movement relative thereto; ball bearings by which said journaling of the starting shaft members on each other is effected having the ball race in one member extended longitudinally of the shaft, and means for effecting such longitudinal movement comprising a sleeve on the shaft forming one side of the ball race, and means for moving the sleeve along the shaft against the balls.
32. An engine starter comprising a casing, a two-membered starting shaft supported in the casing, and consisting of a prime-moving member and an engine-connected member; a power spring in the casing connected with the prime-moving shaft member for rotating the latter by the unwinding of the spring; means for winding the spring from the engine-connected member of the shaft; one-way-driving clutch connections between the two shaft members and ball bearings by which said members are journaled upon each other for relative rotation; said shaft members being relatively movable longitudinally at their said ball bearing and clutch connections.
33. An engine starter comprising a casing, a two-membered starting shaft supported in the casing, and consisting of a prime-moving member and an engine-connected member; a power spring in the casing connected with the prime-moving shaft member for rotating the latter by the unwinding of the spring; means for winding the spring from the engine-connected member of the shaft, one-way-driving clutch connections between the two shaft members consisting of a cup terminal on one of said shaft members into

which the other shaft member intrudes; the said intruded shaft member having at its intruding part a plurality of circumferentially distributed and circumferentially elongated eccentrically bottomed ball pockets, and balls therein for which the cup terminal forms an exterior retainer and ball race.

34. An engine starter comprising the following three elements successively interior each to the preceding and journaled each on the next exterior by ball bearings, viz: a casing; the planet-pinion-carrying member of a planetary gear train, and the prime-moving member of a starting shaft; and comprising also the master gear of the planetary train and an engine-connected member of the starting shaft both journaled by ball bearings on the prime-moving member of the starting shaft.

35. An engine starter comprising the following three elements successively interior each to the preceding and journaled each on the next exterior by ball bearings, viz: a casing; the planet-pinion-carrying member of a planetary gear train, and the prime-moving member of a starting shaft; and comprising also the master gear of the planetary train and an engine-connected member of the starting shaft both journaled by ball bearings on the prime-moving member of the starting shaft, the engine-connected member of the starting shaft being longitudinally movable relatively to the prime-moving member at the ball bearing connection between said two shaft members.

36. An engine starter comprising the following three elements successively interior each to the preceding and journaled each on the next exterior by ball bearings, viz: a casing; the planet-pinion-carrying member of a planetary gear train, and the prime-moving member of a starting shaft; and comprising also the master gear of the planetary train and an engine-connected member of the starting shaft both journaled by ball bearings on the prime-moving member of the starting shaft, the two members of the starting shaft having one-way-driving clutch connection which also constitutes a ball bearing between said members.

37. An engine starter comprising the following three elements successively interior each to the preceding and journaled each on the next exterior by ball bearings, viz: a casing; the planet-pinion-carrying member of a planetary gear train, and the prime-moving member of a starting shaft; and comprising also the master gear of the planetary train and an engine-connected member of the starting shaft both journaled by ball bearings on the prime-moving member of the starting shaft, the engine-connected member of the starting shaft having a disengageable clutch connection with the

planet-gear-carrying member and being longitudinally movable relatively to the prime-moving member at the ball bearing connection between said two shaft members, for engaging and disengaging said clutch connection.

38. An engine starter comprising the following three elements successively interior each to the preceding and journaled each on the next exterior by ball bearings, viz: a casing; the planet-pinion-carrying member of a planetary gear train, and the prime-moving member of a starting shaft; and comprising also the master gear of the planetary train and an engine-connected member of the starting shaft both journaled by ball bearings on the prime-moving member of the starting shaft, the engine-connected member of the starting shaft having a disengageable clutch connection with the planet-gear-carrying member and being longitudinally movable relatively to the prime-moving member at the ball bearing connection between said two shaft members, for engaging and disengaging said clutch connection, and means for causing such longitudinal movement for clutch disengagement comprising a sleeve which forms one member of the ball race for the ball bearing between the two shaft members and which slides on one shaft member pressing against the balls to cause the movement of the other shaft member.

39. An engine starter comprising the following three elements successively interior each to the preceding and journaled each on the next exterior by ball bearings, viz: a casing; the planet-pinion-carrying member of a planetary gear train, and the prime-moving member of a starting shaft; and comprising also the master gear of the planetary train and an engine-connected member of the starting shaft both journaled by ball bearings on the prime-moving member of the starting shaft, said prime-moving member having an additional ball bearing on the casing at a plane remote from the plane of the bearing of the planet-gear-carrying member on the casing.

40. An engine starter comprising the following three elements successively interior each to the preceding and journaled each on the next exterior by ball bearings, viz: a casing; the planet-pinion-carrying member of a planetary gear train, and the prime-moving member of a starting shaft; and comprising also the master gear of the planetary train and an engine-connected member of the starting shaft both journaled by ball bearings on the prime-moving member of the starting shaft, said prime moving shaft member having an additional ball bearing on the casing at a plane remote from the plane of the bearing on the planet-gear-carrying member.

41. An engine starter comprising the following three elements successively interior each to the preceding and journaled each on the next exterior by ball bearings, viz: a 5 casing; the planet-pinion-carrying member of a planetary gear train, and the prime-moving member of a starting shaft; and comprising also the master gear of the planetary train and an engine-connected member 10 of the starting shaft both journaled by ball bearings on the prime-moving member of the starting shaft, said prime-moving member having an additional ball bearing on the casing at a plane remote from the 15 plane of the bearing of the planet-gear-carrying member on the casing, and a power spring in the casing engaged therewith at one end and engaged at the other end with the prime-moving shaft member inter- 20 mediate the bearings of said shaft member on the casing and on the planet-gear-carrying member respectively.

42. An engine starter comprising the following three elements successively interior 25 each to the preceding and journaled each on the next exterior by ball bearings, viz: a casing; the planet-pinion-carrying member of a planetary gear train, and the prime-mov-

ing member of a starting shaft; and comprising also the master gear of the planetary 30 train and an engine-connected member of the starting shaft both journaled by ball bearings on the prime-moving member of the starting shaft, said prime-moving member having an additional ball bearing on the 35 casing at a plane remote from the plane of the bearing of the planet-gear-carrying member on the casing, and a power spring in the casing coiled about the prime-moving member of the starting shaft and attached at 40 one end thereto, and at the other end to the casing; its attachment to the shaft member being intermediate both longitudinally and radially of said shaft member between the ball bearing of the shaft member on the 45 casing and the ball bearing of the planet-gear-carrying member on the casing.

In testimony whereof I have hereunto set my hand in the presence of two witnesses at New York city, county and State of New 50 York this 9th day of November, 1915.

JOHN K. STEWART.
